FOOTBALL GAME BOARD

Ziggie Wahaski, Hayward, Calif., assignor of one-half to Roy A. Jensen, Hayward, Calif.

Application March 10, 1955, Serial No. 34,970

Term of patent 14 years

(Cl. D34—5)

I claim:

The ornamental design for a football game board, substantially as shown.
